PREGNANCY DIAGNOSTIC APPARATUS

Gilbert Roger Corneille, Paris, France, assignor to
Laboratoire Theranol, Paris, France

Continuation-in-part of abandoned design application Ser.
No. 477,344, June 7, 1974. This application Oct. 1,
1975, Ser. No. 618,417

Term of patent 14 years

Int. Cl. D9—03; D24—02
U.S. Cl. D83—1 U

FIG. 1

FIG. 2

FIG. 3

FIG. 4

FIG. 5

FIG. 6

FIG. 1 is a perspective view of a pregnancy diagnostic apparatus, showing my new design;

FIG. 2 is a side elevational view of said apparatus;

FIG. 3 is a rear view thereof;

FIG. 4 is a perspective view of a modified form of the pregnancy diagnostic apparatus illustrated in FIG. 1;

FIG. 5 is a side elevational view of the apparatus of FIG. 4; and

FIG. 6 is a rear view of the apparatus of FIG. 4.

This application is a continuation-in-part of design application Ser. No. D. 477,344 filed June 7, 1974 and now abandoned.

I claim:

The ornamental design for a pregnancy diagnostic apparatus, as shown and described.
